Primary Examiner — R. Johnson(74) Attorney, Agent, or Firm — Jose Cherson Weissbrot(57) CLAIM

The ornamental design for a mute for brass instrument, as shown and described.

DESCRIPTION

FIG. 1 is a perspective view of a mute for brass instrument showing my new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken lines shown in the drawings depict portions of the mute for brass instrument in which the design is embodied that form no part of the claimed design.
